UNITED STATES PATENT OFFICE.

ROBERT O. HOFFMAN, OF JACKSON, MISSISSIPPI, ASSIGNOR, BY DIRECT AND MESNE ASSIGNMENTS, OF ONE-TWELFTH TO THOS. E. BIRD, OF PENSACOLA, FLORIDA, TWO-SIXTHS TO MOSES IRALSON, OF CHICAGO, ILLINOIS, ONE-TWELFTH TO THE DELTA CIGAR & VENDING MACHINE COMPANY, OF DELTA, OHIO, A CORPORATION OF OHIO, AND ONE-HALF TO THE CIGAR VENDER SALES COMPANY, OF PENSACOLA, FLORIDA, A CORPORATION.

CIGAR-VENDING MACHINE.

1,205,094.

Specification of Letters Patent. Patented Nov. 14, 1916.

Application filed March 22, 1916. Serial No. 85,859.

To all whom it may concern:

Be it known that I, ROBERT O. HOFFMAN, a citizen of the United States, residing at Jackson, in the county of Hinds, State of Mississippi, have invented a new and useful Cigar-Vending Machine; and I do hereby declare the following to be a full, clear, and exact description of the invention, such as will enable others skilled in the art to which it appertains to make and use the same.

This invention relates to the art of vending machines, and particularly to an improved coin controlled machine for vending cigars and the like.

One of the objects of the invention is to provide an improved machine of this kind having simple, efficient and practical features of construction over the construction of the vending machine set forth and claimed in the patent issued to Robert O. Hoffman, April 6, 1915, Patent No. 1,134,742.

One of the features of construction is the provision of a cigar delivering slide for delivering a cigar first from one compartment, and then from another.

Another feature of the invention is the provision of an improved detent designed to be partially actuated by a coin, so as to release the slide, which in turn, by virtue of a cam on the slide further actuates the detent to release the coin.

Another feature of the invention is the provision of a supporting plate for supporting one end of each cigar prior to moving the slide, and after having moved the slide, the supported end of the cigar is released from the plate, and is delivered laterally from the machine.

In practical fields the details of construction may necessitate alterations, falling within the scope of what is claimed.

The invention comprises further features and combination of parts, as hereinafter set forth, shown in the drawings and claimed.

In the drawings: Figure 1 is a view in perspective of the improved cigar vending machine constructed in accordance with the invention. Fig. 2 is a vertical sectional view on line 2—2 of Fig. 1. Fig. 3 is a sectional view on line 3—3 of Fig. 2, showing one position of the cigar delivering slide.

Fig. 4 is a view similar to Fig. 3 showing another position of the cigar delivering slide. Fig. 5 is a vertical sectional view on line 5—5 of Fig. 2 looking in the direction of the arrow. Fig. 6 is an enlarged detail sectional view of the coin chute, and showing the plunger in elevation, for actuating the coin so that the coin will partially release the detent. Fig. 7 is a detail perspective view of a part of the coin chute and a portion of the detent showing the coin in dotted lines.

Referring more especially to the drawings, 1 designates the lower portion of the casing of the cigar vending machine and 2 the upwardly rising restricted portion, which comprises side parts 3 having the flanges 4, and between which side parts and the flanges 4 thereof the usual cigar box 5 is arranged, the flanges 4 acting to prevent backward and forward movement of the box. The cigar box 5 is provided with a partition 6, so as to form two compartments in the box. Prior to arranging the cigar box in position one of its end pieces is detached, so that the cigars in the compartments may move downwardly. Adjacent where the upper part 2 rises from the lower portion of the casing front and rear pieces 7 and 8 are arranged in the guides 9, there being a center piece of glass 10, which acts as a continuation of the partition 6. The pieces of glass 7 and 8 act as continuations of the parts 11 of the cigar box, when arranged in position. A cover 12 is provided for the upper part 2 of the casing, and which rests upon the beading 13. Secured to the under face of the cover by means of screws 14 is a wood plate or piece 15. Countersunk in the wood piece or plate 15 upon its upper face is a metal plate 16, which is secured to said plate 15 prior to fastening the same to the cover 12. A staple 18 has its arms passing through the plate 15, and the arms have their extremities riveted at 19 to the plate 16. A headed rod 20 is inserted transversely of the upper part of the casing, so as to pass through the staple 18, and is provided with an eye 21 at its end opposite the head of the rod, for the reception of a padlock or the like 22, thereby

locking the rod in place, and preventing the cover 12 from being removed, until it is desired to remove the empty cigar box, for the insertion of a filled box. The lower portion 1 of the casing is provided with a partition 23 dividing the lower portion into upper and lower compartments 24 and 25. A wood plate 26 is secured by screws 27 upon the under face of the partition 23, and embedded in the plate 26 and secured thereto by the screws 28 is a metal plate 29, to which the arms of the staple 30 are riveted as shown at 31. The staple 30 protrudes downwardly through the wood plate 26, and through the base plate 32 of the lower part 1 of the casing, and also through a slot 33 of any suitable stationary support 34, in order to receive the shackle of the usual form of padlock 35, thereby locking the base plate 32 to the lower part 1 of the casing, and also locking the casing to a counter, shelf, or any other suitable stationary support. The slot 33 registers with the slot 36 of the base plate 32. This base plate 32 is provided with a beading 37, which surrounds the lower portion of the part 1 of the casing, thereby preventing the lower edge portion of the part 1 from being separated from the base plate to permit access to the coin compartment 25. One side of the lower part 1 of the casing is provided with a pair of openings 39 and 40, and a slide 41 is arranged in the compartment 24 on the partition 23. This slide adjacent its lower longitudinal sides is provided with flanges 42, which engage the guides 43, whereby the slide may be moved longitudinally of the lower part of the casing. The slide is provided with spaced pockets or recesses 44 and 45, which are disposed transversely and have their bottoms inclined downwardly and laterally toward the openings 39 and 40, which are on a plane slightly below the bottoms of said pockets or recesses, particularly below the higher portions of the bottoms of said pockets.

The side of the lower part 1 of the casing, that is, the side having the openings 39 and 40, is provided with an elongated slot 46, through which the shank 47 of the hand knob 48 extends, which shank is fixed to the slide 41. Adjacent one side the partition 23 is provided with a slot 49, and secured to the partition 23 in order to register with the slot 49 is a coin chute 50, the upper extremity of a branch of which coin chute is fixed by means of the screw 51 and flange 52 to the under face of one end of the top of the part 1 of the casing. The coin chute branch 53 registers with the coin slot 54 of the casing. One side edge of the lower part of the coin chute 50 is provided with a cut-away portion 55, which receives one end 56 of the detent 57 pivoted at 58 to the upper face of one of the guides 43. The end

56 of the detent has a laterally and downwardly extending flange 59, between which and one side edge of the coin chute 50, the coin is designed to engage, that is, when pushed in such a position by means of the plunger 60. The plunger 60 is mounted in a guide 61 of the top of the part 1 of the casing, and has its lower end fitting into an extension 62 of the coin chute 50, there being a spring 63 between the extension 62 and the transverse pin 64 of the plunger 60. After depositing a coin through the slot 54 into the branch 53, it gravitates into the chute 50, in order to rest upon the downwardly and laterally extending flange 59 of the end 56 of the detent. The plunger is then depressed so that its lower end bears against the coin, in order to force it further between the detent and one side edge of the coin chute, in which case the detent is tilted upon its pivot 58 sufficiently, so that the bent ends 66 of the arm 67 of the detent is moved to one side and sufficiently out of the path of the block 68 of the slide, so that by grasping the hand knob 48 the slide may be moved in one direction or the other. The detent is actuated against the action of the leaf spring 69, which is secured at 70 to the upper face of one of the guides 43. It is to be noted that when the end 66 is moved out of the path of the block 68, the slide may be moved in one direction or the other. However, as the slide is moved in one direction, the bent end 66 of the detent rides or cams over the bulged portion 71 of said block 68, which tilts the detent additionally upon its pivot, thereby causing the end 56 of the detent to release the coin, which will drop into the coin compartment. The plunger when pushed downwardly is limited in its downward position sufficiently to only force the coin partially between the flange 59 of the end 56 of the detent and one side edge of the coin chute, so that when the bent end 66 cams over the bulge 71, the end 56 will release the coin. On one side of the lower part 1 of the casing on the interior thereof a supporting shelf or flange 72 is provided, which supports one end of each of the lowermost cigars, while the higher part of the bottom of each pocket or recess 44 and 45 supports the opposite end of each of the lowermost cigars, that is, when the cigar is in the pocket.

In operation, the coin is deposited in the coin chute, the plunger is depressed so as to force the coin sufficiently between the flange 59 and one side edge of the coin chute, so that the bent end 66 of the detent is moved sufficiently from the path of the block 68, whereby the slide may be moved. Say for instance, the slide is in the position shown in Figs. 2 and 3, when the coin is deposited in the coin chute, and has been pushed sufficiently between the end 56 of

the detent and the side edge of the coin chute, to move the bent end 66 from the path of the block 68. The slide by grasping the hand knob 48 may then be moved in the direction of the arrow *a*, which will bring the cigar *b* in dotted lines in Figs. 3, moving one end of the cigar off the shelf or flange 73, so that the cigar *b* will slide out through the opening 40. When moving the slide in this way the bulge 71 further tilts the detent and releases the coin. At the same time moving the slide to this position and delivering the cigar *b* the bottommost cigar in the other compartment of the cigar box will fall into the pocket 44 so that one of its ends is supported by the shelf 73. A cigar is shown in dotted lines in the pocket 44 in the act of passing out through the opening 39. Fig. 4 illustrates the position of the slide after having moved in the direction of the arrow *a*. To deliver the cigar *c* in dotted lines in Fig. 4, the detent is tilted as before, to remove the bent end 66 of the detent from the path of the other end of the block 68, and in this case the slide may be moved in the direction of the arrow *d* in Fig. 4, so as to deliver the cigar *c* through the opening 39.

The invention having been set forth, what is claimed as new and useful is:

1. In a cigar vending machine, the combination of a casing having a plurality of compartments and a plurality of outlet openings, of a reciprocatory delivery member having a plurality of cigar receiving pockets to alternately receive cigars from said compartments for delivery through said openings, and detent means for said member to be operated for releasing said member, whereby said member may alternately deliver cigars from said compartments, said detent means comprising an engageable abutment on said member, a detent lever to engage said abutment to hold the delivery member in one position or another, whereby first one and then another of said pockets alternately register with one of the compartments, means adapted to be actuated to push a coin against and partially operate said lever to move one end of the lever from the path of said abutment, whereby said member may deliver a cigar through one of said openings, said abutment having a cam to be engaged by the lever to release said coin.

In testimony whereof I have signed my name to this specification in the presence of two subscribing witnesses.

ROBERT O. HOFFMAN.
